UNITED STATES PATENT OFFICE

CHARLES E. GILLESPIE, OF SEYMORE, INDIANA

COMPARTMENT BUILDING

Application filed June 11, 1931. Serial No. 543,537.

The present invention relates to compartment buildings, and more particularly to means whereby sleeping and dressing compartments may be provided, the compartments being so constructed as to occupy a minimum of space.

An object of the invention is to provide a pair of spaced dressing compartments, each of said dressing compartments having connected therewith a sleeping compartment, one of the sleeping compartments being superimposed upon the other, whereby a maximum of usable space may be provided to occupy a minimum of ground space. A further object of the invention is to provide means whereby a storeroom, or the like, may be converted into individual sleeping compartments for a great number of persons. A further object of the invention is to provide a plurality of portable units, each comprising two dressing rooms and two sleeping compartments, said units being capable of arrangement in a storeroom, or the like, to provide private sleeping quarters for a great number of people. A further object of the invention is to provide, in connection with units of the character described, means for ventilating the storeroom and said units. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a horizontal section, taken in two planes, of a building in which are arranged a plurality of units of the character described;

Fig. 2 is a perspective view of a unit constructed in accordance with the present invention;

Fig. 3 is a transverse sectional view therethrough;

Fig. 4 is a fragmental section similar to Fig. 3, but drawn to a larger scale;

Fig. 5 is a fragmental section in a plane

parallel to the plane of Fig. 3 but drawn to a larger scale; and

Figs. 6 and 7 are fragmental sections illustrating the louvre construction.

Referring more particularly to the drawings, it will be seen that I have illustrated a building, indicated generally at 10, said building having opposite end walls 11 and 12 provided with induction and eduction fans, respectively. Within said building are arranged one or more series of units 13.

Each of said units 13 is preferably formed of a plurality of sheet metal walls. The side wall 14 may rest upon a floor 15, and a pair of end walls 16 and 17 are secured, respectively, to the opposite ends of said side wall 14. A horizontal wall 18 is secured to the upper edges of the walls 14, 16, and 17, and said wall 18 is formed with one or more apertures 19 covered by a plate 20 secured to upstanding legs 21, which may be integrally formed with the wall 18.

An intermediate wall 22 is secured to the free edge of the wall 18, and is disposed in a plane parallel to the plane of the wall 14. The upper edge 23 of the wall 22 is disposed above the level of the wall 18, and the lower edge 24 of said wall 22 is disposed below the level of the wall 18.

A second pair of end walls 25 and 26 are secured to the opposite ends of the wall 22 in alignment with the walls 16 and 17, and said walls 25 and 26 are respectively secured to the free edges of the walls 16 and 17, it being understood that the walls 25 and 26 may be integral with the walls 16 and 17.

A horizontal wall 27 is secured to the upper edges of the walls 22, 25, and 26, and said wall 27 is formed with an aperture 28 covered by a plate 29 supported above the plane of the wall 27 by lugs 30 which may be integral with the wall 27.

A second intermediate wall 31 is disposed in a plane parallel with the planes of the walls 14 and 22, and is secured to the free edges of the walls 25 and 26. The upper edge 33 of the wall 31 is disposed substantially in, or slightly above, the plane of the edge 24 of the wall 22; and the lower edge 32 of said

wall 31 is preferably disposed somewhat above the level of the floor 15.

A third intermediate wall 34 is secured to the free edge of the horizontal wall 27, and is disposed substantially in the plane of the second intermediate wall 31, said wall 34 projecting upwardly from its line of engagement with the wall 27. To the upper edge 35 of the wall 34 there is secured a third horizontal wall 36, said wall being formed with an aperture 37 covered by a plate 38 supported above the level of the wall 36 by lugs 39 which may be integral with wall 36.

A horizontal floor plate 40 projects laterally from the intermediate wall 31, said plate 40 being supported upon brackets 41 secured to said wall 31 intermediate the upper and lower edges thereof, each of said brackets 41 being formed with a downturned lip 42 secured to the wall 31 by screws 43, or other equivalent fastening means. Each bracket 41 may include a diagonal support 44 having a portion 45 secured to the wall 31 adjacent the lower end thereof by means of screws 46, or the like.

A third pair of end walls 47 and 48 are respectively secured to the opposite edges of the walls 31 and 34, the horizontal wall 36, and the floor plate 40. A second side wall 90 is secured to the walls 47, 48, and 36, and to the floor plate 40. Legs 49 may be provided to assist in stabilizing the unit.

It is to be noted that, if desired, the walls 14, 16, 17, and 18 may be integral; the walls 22, 25, 26, 27, and 31 may be integral; and the walls 34, 36, 47, 48, 90, and 40 may be integral. Obviously, the metal sheets making up the walls may be combined in other integral arrangements to provide the illustrated positioning of walls.

An angle iron 50 is secured to the upper edge 33 of the wall 31. Similar angle irons may be secured to the lower edge 24 of the wall 22, and to the walls 25 and 26, the horizontal flanges of all of said angle irons being disposed in the same plane. A sheet 51 of suitable material is carried on the horizontal flanges of said angle irons, and said sheet, together with the frame 52 of a set of springs 53 and a mattress 54 supported on said springs, forms a horizontal partition dividing the chamber defined by the walls 22, 25, 26, 27, and 31 into two compartments, one above the other.

An angle iron 55 may be secured to the wall 31 adjacent its lower end 32, and other angle irons may be secured to the walls 25 and 26 and to uprights 80, the horizontal flanges of all of said angle irons being disposed in the same plane, to support a spring series 56 upon which is mounted a second mattress 57.

It will be seen that the described organization provides a dressing chamber 58, the floor of which is formed by the building floor 15; a sleeping chamber 59 projecting later-

ally from said dressing chamber 58, and opening thereinto; a second dressing chamber 60, the floor of which is formed by the floor plate 40 disposed at a level materially above the level of the floor 15; and a second sleeping chamber 61 projecting laterally from the chamber 60 and opening thereinto; said chamber 61 being disposed above the chamber 59, and the bed within said chamber 61 forming the only partition between the chambers 61 and 59.

The wall 14 is preferably formed with an opening 62 adapted to be closed by a door 63 hung upon hinges 64. Said wall 14 is likewise formed with a series of upwardly and inwardly opening louvres 65 and with a second series of downwardly and inwardly opening louvres 66. The louvres 65 and 66 are so designed and positioned as to prevent a view of the bed, comprising the mattress 57, through either set of louvres 65 or 66.

Vertical louvres 67 are likewise formed in the wall 14, said louvres opening inwardly and toward the adjacent end wall 16 or 17. No vertical louvres are formed in the door 63 because, said door being located substantially centrally of the length of the wall 14, vertical louvres opening in either direction would permit a view of the bed 57.

The walls 22 and 34 are likewise formed with horizontal louvres 69 and 70 and with vertical louvres (unnumbered). All of the louvres 69 and 70 open inwardly and upwardly. The vertical louvres in the walls 22 and 34 open inwardly and toward the adjacent end walls. Horizontal louvres are likewise formed in all of the end walls, said louvres opening inwardly and upwardly or downwardly in accordance with the positions of the louvres. The end wall 48 is formed with an opening 71 adapted to be closed by a door 72 supported on hinges 73. Because of the fact that the hinged edge of the door 72 is disposed very close to the wall 90, vertical louvres may be provided in the door 72, said louvres opening inwardly and toward the wall 90.

A platform 74 disposed substantially in the plane of the floor plate 40 gives access to the chamber 60; a set of stairs 75 lead to said platform 74, and said platform and stairs being guarded by a hand rail 76.

While the unit 13 may be used alone either within a building or outdoors, I prefer to use a series of such units in the arrangement illustrated in Fig. 1. In Fig. 1, I have illustrated a building in which a plurality of units 13 are arranged in two series on opposite sides of a center aisle extending longitudinally of the building. A cashier's desk or booth 77 is preferably located within the aisle and adjacent the entrance to the building, and a social or waiting room 78 may be provided adjacent the cashier's booth. A bathroom 79 may be provided in the build-

ing, and I have shown stairs 91 leading to a second floor where two more series of units 13 may be arranged on opposite sides of a longitudinal aisle.

5 It will be seen that each unit 13 may be considered as made up of two elements, one comprising the chamber 58 and the communicating chamber 59, and the other comprising the chamber 60 and the communicating chamber 61, the chamber 61 being superimposed upon the chamber 59 and separated therefrom solely by the bed within the chamber 61, and the two chambers 58 and 60 being separated by the chambers 59 and 61.

15 I claim as my invention:

1. A knock-down chamber comprising end walls and side walls, and a pair of spaced intermediate walls substantially parallel with said side walls, the lower edge of one of said intermediate walls being disposed substantially in the horizontal plane of the upper edge of the other intermediate wall, a bed secured to said edges of said intermediate walls and to said end walls and forming a partition dividing said chamber into two independent compartments, a second bed secured to said end walls and disposed vertically beneath said first bed, and other walls cooperating with said end walls to form two non-communicating compartments, each communicating with one only of said beds, certain of said walls being formed to permit access to said compartments.

2. As an article of manufacture, a unit comprising walls forming a chamber, vertical walls within said chamber, a bed cooperating with said walls within said chamber to divide said chamber into two non-communicating compartments, said bed being accessible from one of said compartments, and a second bed disposed vertically below said first bed and accessible from the other of said compartments, two of said vertical walls being formed with doorways, each giving access to one only of said compartments.

3. As an article of manufacture, a unit comprising walls forming a chamber, vertical walls within said chamber, a bed cooperating with said walls within said chamber to divide said chamber into two non-communicating compartments, the floors of said compartments being at different levels, and said bed being accessible only from that compartment having the higher floor level, and a second bed accessible only from that compartment having the lower floor level, two of said vertical walls being formed with doorways, each of said doorways giving access to one only of said compartments, and said doorways being located at different levels.

4. An article of manufacture comprising walls defining a central chamber, a bed horizontally disposed in said chamber, means including said bed dividing said chamber into two, non-communicating, vertical-

ly aligned compartments, a second bed in said chamber beneath said first bed, and other walls associated with said first-named walls and defining a pair of flanking chambers associated with said first chamber and 70 communicating individually with said respective compartments, certain of said walls being formed with access openings.

5. An article of manufacture comprising 75 walls defining a central chamber, a bed horizontally disposed in said chamber, means including said bed dividing said chamber into two, non-communicating vertically aligned compartments, said bed being accessible from one of said compartments only, a second bed 80 in said chamber beneath said first bed and accessible from the other of said compartments only, and other walls defining a pair of flanking chambers associated with said first chamber and communicating individually with said respective compartments.

6. An article of manufacture comprising 85 walls defining a central chamber, a bed horizontally disposed in said chamber, means including said bed dividing said chamber into two, non-communicating, vertically aligned compartments of less than normal head-height, a second bed in said chamber beneath said first bed, other walls cooperating with said first-named walls to define a 90 pair of flanking chambers of at least normal head-height associated with said first chamber, one of said flanking chambers giving access to said second bed and having its floor disposed beneath the level of said second bed, 100 and the other of said flanking chambers giving access to said first bed and having its floor disposed beneath the level of said first bed and above the level of said second bed, a 105 door for each of said flanking chambers and a stairway leading to the door for said last-mentioned flanking chamber.

In witness whereof, I, CHARLES E. GILLESPIE, have hereunto set my hand at Seymour, Indiana, this eighth day of June, A. 110 D. one thousand nine hundred and thirty-one.

CHARLES E. GILLESPIE.
